UNITED STATES PATENT OFFICE.

CLARENCE A. VETTER, OF PITTSBURGH, PENNSYLVANIA, ASSIGNOR, BY MESNE ASSIGNMENTS, TO BEST ELECTRIC COMPANY, A CORPORATION OF DELAWARE.

LAMP-SOCKET.

1,078,813.

Specification of Letters Patent.

Patented Nov. 18, 1913.

Application filed September 24, 1912. Serial No. 722,150.

To all whom it may concern:

Be it known that I, CLARENCE A. VETTER, a citizen of the United States, residing at Pittsburgh, in the county of Allegheny and State of Pennsylvania, have invented certain new and useful Improvements in Lamp-Sockets, of which the following is a specification.

My invention refers to the class of sockets of incandescent lamps.

It has for its object to provide a "keyless" socket adapted to operate for making and breaking the current by rotation of the lamp and its base within a receiving portion of a socket, which portion is rotatably secured to a fixed portion of a socket, in such a manner as to prevent separation.

The device is so constructed as to provide for opening and closing the circuit to the lamp filaments and to prevent removal of the lamp after being once inserted, without destruction. This feature is important and one of the valuable characteristics of the device, so as to prevent loss of lamps.

The invention, as constructed, and for the purpose of accomplishing such objects, consists generally of a base portion of insulating material having terminal connections, a relatively rotatable lamp holding portion, and an outer protecting shield construction, and adapted to operate in the manner more fully hereinafter described.

Referring now to the drawings illustrating one preferred form of the invention Figure 1 is a view in side elevation of a complete socket and lamp. Fig. 2 is an enlarged vertical sectional view through the base, indicated by the line II. II. of Fig. 3. Fig. 3 is a plan view of the upper relatively stationary base, indicated by the horizontal section line III. III. of Fig. 2. Fig. 4 is a perspective detail view of the rotatable base, detached. Fig. 5 is a plan view of the rotatable base, illustrating a modified construction. Fig. 6 is a sectional detail view showing means for temporarily holding the rotatable base.

In the drawings, the base is generally designated by the letter A and is adapted to receive and support an ordinary standard electric lamp bulb B, which is provided with the usual threaded socket portion b. The base A is surrounded by a two-part cap or shield a, a', overlapping and interfitting the

one with the other in the customary way, the shell a' having the reduced annular extension a² extending over and surrounding the base portion b of the lamp B. Such parts of the construction are of ordinary and well-known form, and the cap a is provided with a terminal neck, through which are introduced the current supply wires c, d. Within the upper portion of the shell is fixedly secured the insulating base 2 made of porcelain, fiber, or other suitable material, to which is rotatably connected the rotatable base 3 by a central stem or pin 4. Said pin may be in the form of a screw, as shown, the lower end of which is provided with a screw head 5, the upper end having a nut 6, suitable washers 7 and 8 being provided at each end for insuring free rotation. As thus connected it will be seen that, when the parts are assembled and a lamp is inserted, access to the connecting stem 4 is absolutely prevented.

The washer 8, at the upper end of stem 4, is extended downwardly to one side of the base 2 within a suitable receiving recess therein and turned downwardly, and it is provided with a terminal binding post connection, as a screw 9, by which one of the terminals d is connected therewith and in electrical communication with the stem 4. The central portion of the lamp base b makes contact against the lower end of stem 4, and its washer 7, thereby establishes one of the circuit connections with the filaments. The base 2 is provided with a pair of spring controlled contact terminals 10 and 10' mounted in suitable bushings 11 and 11' respectively, having springs 12 and 12' respectively, seated at their inner ends against retaining screws or abutments 13 and 13' respectively. But one of such terminals, 10, is utilized for conducting the current, for which purpose a washer extension 14 is secured by screw 13 against bushing 11, and extends outwardly, downwardly and laterally by an extension 15, having a binding screw 16 for attachment of the other conductor c. The opposite spring-actuated terminal 10' is merely for the purpose of centralizing or balancing the bearing engagement of the base 2 against base 3.

For the purpose of providing for circuit establishing and interlocking engagement between the bases, the rotatable base 3 is pro-

vided with annularly arranged conducting contact members 17, 17, each of which is in circuit connection by screws 18, 18 with the base of the threaded receiving shell 19, into which the base *b* of the lamp B is screwed, as is Fig. 2.

Arranged between the conducting segments 17 are corresponding non-conducting segments 20, 20, of insulating material, the ends of which abut against the ends of the conducting members 17. Each of such members is provided with a spirally ascending bearing face, as clearly shown in Fig. 4, and one end of the insulating members 20 is offset, as at 21, providing a retaining shoulder for the spring-controlled pins 10 and 10'. Shoulder 21 is formed integrally with the insulating portion of the segment, so that in the operation of the device, when pin 10 or 10' rides over from the conducting segment 17 and on to the insulating member 20, it will bear by its side and end portion against insulation only, thereby absolutely preventing any circuit. The other end of each segment 20 merely abuts against the end of conducting segment 17, its bearing face being flush therewith, so that the pin will ride smoothly over from one to the other and come into circuit establishing bearing with segment 17.

From the foregoing description it will be clearly seen that the shell 19 being fixedly secured to the rotatable base 3, the lamp base may be tightly screwed into the threaded portion of the shell 19 clockwise, the pins 10 and 10' holding the base 3 and shell 19 fixedly against rotation in that direction. The lamp having been thus tightly screwed into the base, with sufficient binding force, the lamp and base may then be rotated backwardly with base 3 quite freely to any extent, the spiral face of the insulating and conducting segments 17 and 20 respectively riding underneath the pins 10 and 10' which will successively fall behind the shoulders 21, locking the base 3 against rotation "clockwise," while the rotation of the lamp and base in the opposite or backward direction will effect the making and breaking of the circuit alternately, as desired.

The extension of the shell *a'* downwardly around the base of the lamp and shell 19 positively prevents the holding of the shell by any means, so as to prevent tampering with or unscrewing of the lamp therefrom. If, however, it is desired to provide the device with means for temporarily holding the rotatable base so that the lamp may be unscrewed from the shell 19, as in the case of private or domestic use of lamps, where there is no danger of theft, and where it is also desirable to remove the lamp bulb without breaking the globe, I provide the locking device 22 (Fig. 6) consisting of a pin or stud carried by a spring 23 on the shell

a' extending inwardly therethrough and adapted to register with a companion socket 24 of the rotatable base 3'. The stud 22 is normally held out of engagement with the socket 24 by retraction of the spring 23 and when pressed inwardly and the base 3' is rotated in the usual way, it will spring into engagement and may be thus held, locking the rotatable base against reversal, and allowing the lamp to be unscrewed in the usual manner. Otherwise the making and breaking of the circuit may be accomplished in the manner already described.

If it is desired to merely prevent unscrewing of the lamp but without turning the current on or off, the segment construction of the spiral bearing ring shown in Fig. 4 may be substituted by a continuous ring 25 of conducting material, in contact communication with shell 19 and merely having one or more shoulders 21', preferably two for equalization of bearing for each pin, as in Fig. 5. In such case the current will be maintained at any position, but the shoulders 21' will interlock with the pins 10 and 10' allowing for screwing in of the lamp in the manner described, but preventing unscrewing due to the free rotation of the ring with relation to the locking pins in the manner already described. In such case the current to the lamp may be controlled by other well known means, as by a wall key or switch.

The advantages of the invention will be readily understood and appreciated from the foregoing description. The device is especially adaptable to use with group arrangements of lamps, as in candelabra or other installations. One or any desired number of the lamps may be readily thrown out of circuit by merely partly turning one or more of the lamps while maintaining the full circuit supply to all of the bases. Also, each lamp is maintained in continuous normal circuit conducting contact with the conducting elements of the base, so that all danger of short circuiting, burning of insulation, etc., is avoided.

What I claim is:

1. The combination of a lamp-carrying part, a terminal wire-carrying part, a swivel connection, spring-actuated pins on one of said parts, and shoulders on the other part, said pins and shoulders coöperating to jam or lock the lamp against removal.

2. A lamp socket consisting of a base provided with a central swiveling stem and a laterally arranged spring-actuated locking abutment each forming conducting members, terminal wire connections in circuit therewith, a relatively rotatable lamp supporting base swiveled on said stem having a spirally threaded lamp receiving shell on its outer portion and a shouldered locking ring on its inner portion co-acting with said spring-

actuated locking abutment, and means connecting the lamp receiving shell with the locking ring, substantially as set forth.

3. A lamp socket consisting of a base provided with a central swiveling stem and a laterally arranged spring-actuated locking abutment each forming conducting members, terminal wire connections in circuit therewith, a relatively rotatable lamp supporting base swiveled on said stem having a spirally threaded lamp receiving shell on its outer portion and a locking ring on its inner portion composed of segmental shouldered insulating sections and alternating conducting sections forming therewith spirally inclined bearing faces, and means connecting the lamp receiving shell with the conducting sections, substantially as set forth.

4. A lamp socket consisting of a base provided with a central swiveling stem and a laterally arranged spring-actuated locking abutment each forming conducting members, terminal wire connections in circuit therewith, a relatively rotatable lamp supporting base swiveled on said stem having a spirally threaded lamp receiving shell on its outer portion and a shouldered locking ring on its inner portion co-acting with said spring-actuated locking abutment for arresting the lamp receiving shell against rotation upon screwing a lamp thereinto and for permitting free rotation of the tightly inserted lamp and shell in the opposite direction, and means connecting the lamp receiving shell with the locking ring, substantially as set forth.

5. In a lamp socket, the combination of a base portion having binding post connections for current supply wires, a central swivel pin in circuit with one of said connections, a spring-actuated stud abutment and mounting therefor in circuit with the other of said connections, a relatively rotatable base swiveled on said pin, the pin extending therethrough and providing a central lamp contact, and a shouldered conducting ring and a lamp socket secured on

the inner side of said rotatable base and connected to each other adapted to engage said abutment and offer resistance to effect tight insertion of a lamp in the direction of screwing into the socket and to permit free reversal of the lamp and socket in reverse direction, substantially as set forth.

6. In a lamp socket, the combination of a base portion having binding post connections for current supply wires, a central swivel pin in circuit with one of said connections at its inner end and forming a lamp contact by its outer end, a spring-actuated abutment and mounting therefor in circuit with the other of said connections, a relatively rotatable base swiveled on said pin, a spiral ring composed of conducting and non-conducting segments embodying insulating abutments, and a lamp socket secured on said rotatable base and connected with the conducting segments of said ring, substantially as set forth.

7. In a lamp socket, the combination of a base portion having binding post connections for current supply wires, a central swivel pin in circuit with one of said connections at its inner end and forming a lamp contact by its outer end, a spring-actuated abutment and mounting therefor in circuit with the other of said connections, a relatively rotatable base swiveled on said pin, a spiral ring composed of conducting and non-conducting segments embodying insulating abutments, a lamp socket secured on said rotatable base and connected with the conducting segments of said ring, and a protecting shell surrounding said bases and extending over the lamp socket and inclosing the circuit controlling means, substantially as set forth.

In testimony whereof I hereunto affix my signature in the presence of two witnesses.

CLARENCE A. VETTER.
